ROBERT K. WINNING, OF MILWAUKEE, WISCONSIN, ASSIGNOR TO CLUM MANUFACTURING COMPANY, OF MILWAUKEE, WISCONSIN.

VEHICLE LAMP.

Application filed February 11, 1924. Serial No. 692,014.

This invention relates to improvements in vehicle lamps. More particularly, this invention relates to improvements in a novel type of lamp which is especially adapted to be mounted upon the cowl of a motor vehicle, but which may be found useful for various other purposes.

Broadly speaking, it is the primary object of this invention to provide a novel and simple construction such as is adapted to facilitate manufacturing processes and to result in a cheap, sturdy lamp which will be satisfactorily and readily operative for whatever purposes it may be intended. More specifically stated, it is my object to produce a lamp construction in which the several parts will not only be adapted for cheap manufacture but will also co-operate with each other in the assembled product in such a manner as to retain each other in place in a simple and effective manner.

In the drawings:

Figure 1 is a side elevation of a lamp embodying this invention, portions thereof being broken away to an axial vertical section.

Figure 2 is a front elevation of said lamp with portions broken away to a central transverse vertical section.

Figure 3 is a plan view of the lamp with a part of its casing cut away to expose the bulb socket and adjacent parts in plan.

Figure 4 is a plan view of the blank from which the lamp standard is constructed.

Figure 5 is a detail view in front elevation of a portion of the lamp, showing the glass retaining ring retained in place and showing the bulb in place within its socket.

Like parts are identified by the same reference characters throughout the several views.

The body 1 of the lamp comprises a portion 2 of generally cylindrical form, a concave back portion 3 formed to serve as a reflector, and a marginal flange or bezel 4 in which the glass 5, comprising the face of the lamp, is adapted to be received. The body 1 may be formed conveniently by a stamping or drawing operation, and after its general shape is determined, along the lines indicated above, I preferably form therein by pressure a substantially horizontal flat bottom indicated at 6.

In the preferred embodiment of this invention the flat bottom above referred to is made by pressing downwardly as at 7 the

metal adjacent its extreme lateral portions, and by pressing inwardly as at 8 the metal adjacent its central portions. In other words, the area 6 comprises a substantially plane surface of which the lateral marginal portions are outside of the arc represented by the wall of the cylindrical body portion 2, and the central portion 8 is within said arc and comprises a chord thereof. By forming the plane portion 6 of the lamp body in this manner I am able to provide said surface with a minimum of distortion of the metal of the body. The metal in the marginal portion 7 and the central portions 8 is pressed only slightly out of its original position to lie in an intermediate plane, whereas if either of such portions were forced the entire distance to lie in the original plane of the other, a far greater distortion of the metal would be required. The flat area 6 will be hereinafter designated as the body disk.

The base 10 is designed to conform in shape to the surface to which it is to be applied and is provided with screw holes 11 to facilitate its application to such a surface. It is provided at 12 with a disk adapted in the completed article to be parallel to disk 6 of the body. The disk portion 12 of the base is pressed from the base entirely in one direction (away from the face which is to contact with the vehicle) instead of being formed by the method used in the formation of the disk portion 6 of the body.

Centrally of disks 6 and 12, I provide apertures 13 and 14 which are preferably generally circular but have in their peripheries numerous notches 16. In corresponding portions of one aperture there is also a notch 17 which will preferably be double the peripheral extent of notches 16. I have found it convenient to dispose the double notch in that side of the aperture which lies in the direction of the front side of the lamp.

For the purpose of connecting the base 10 and the body 1 of the lamp, I provide a standard 20 which may be conveniently formed from a flat blank shaped as indicated in Figure 4. This blank will include side margins 21 and 22 from which project laterally at intervals tongues 23. The ends 24 and 25 of the blank will be formed for mutual abutment, and adjacent each end will be found one of the tongues 23 above referred

to. The arrangement is such that the blank may be rolled to bring into abutment its end portions 24 and 25, whereby there is formed a cylindrical split ring. This ring comprises the standard 20, and its axially projecting tongues 23 are so spaced as to be receivable into the slots 16 and 17 about the peripheries of apertures 13 and 14 in the lamp body and base respectively. The arrangement is such that the closely contiguous tongues 23, which were located immediately adjacent the ends of the blank, will be received together into the special notches 17 which were referred to above. The split ring will thereby be keyed by disk portions 6 and 12 of the body and the base in such a manner that its split ends are inseparable unless the lamp be demolished. To retain the parts in this position, the extremities of tongues 23 are bent over the adjacent marginal portions of the disks and thereby serve to confine such marginal portions of disk 6 against margin 21 of the standard, and the marginal portions of disk 12 against the margins 22 of the standard. Thus, the base and body of the lamp are permanently and securely joined together.

There is formed in the blank from which the standard is formed, or else in the completed standard, a recess or chamber which is indicated generally at 27. In this recess one portion 28 may be in the end 25 of the blank from which the standard is formed, and the other portion 29 of the recess may be in the end 24 of said blank. As shown in the drawings, the recess is preferably rectangular in elevation and is of a depth corresponding substantially to the thickness of the metal of which its walls are composed. Semi-circular pieces of metal are cut from each end of the blank within the confines of the recess to provide a hole 30 to be disposed centrally in the completed standard 20.

The internally threaded sleeve 32 is preferably constructed integrally with a rectangular base flange 33 receivable within the recess of chamber 27. The aperture 30 is of sufficient diameter to receive sleeve 32 with a close fit. Consequently, when the body 1, base 10, and standard 20 of the lamp have been assembled in the manner already described, the sleeve 32 can readily be pressed outwardly through aperture 30 until the base flange 33 of said sleeve rests within the recess 27 formed in the wall of the standard.

At this time a socket sleeve 35 will be pressed downwardly within the standard 20 until an arcuate rib 36 formed therein contacts with the bent over extremities of tongues 23 of the standard. These lugs 36 are oppositely disposed and comprise limiting members, whereby to determine the extent to which socket sleeve 35 may be forced downwardly. The socket sleeve will be noted to have a comparatively close fit within the

standard 20 and will consequently be retained frictionally within the standard. To ensure that it will not be displaced, however, I prefer to upset or rivet its extremities in the manner indicated at 37 so that it will be impossible to withdraw the socket sleeve without destroying it. It is particularly to be noted that with the socket sleeve in the position indicated, the intermediate portion of the wall of said sleeve will serve not only to re-enforce and stiffen column 20, but also to back up and secure against displacement the flange 33 of the internally threaded member 32. Said flange is confined by sleeve 35 in recess 27 and cannot possibly be displaced therefrom.

The socket sleeve 35 is provided with L-shaped slots at 38, whereby it is adapted to serve as a bayonet socket to receive a standard lamp. Its length will be such as to position the lamp accurately within the body 1. The sleeve is also provided with inwardly pressed integral fingers 39 which are adapted to receive and support a well known type of plug, whereby such plug will be in position to make operative contact with the base of a lamp in the bayonet socket provided by the sleeve. The plug is indicated at 50 with a wire leading thereto. It is not thought necessary to give the details of the interior construction of the plug since it is a commercially available article and forms no part of the present invention. For the purposes of support from the fingers 39 the plug may be formed with L-shaped grooves to comprise an inversion of an ordinary bayonet socket.

The glass 5 of the lamp is held in place by the simple expedient of the retaining ring 40 including a band portion 41 and an inwardly projecting flange 42. In its uppermost portion the band 41 is provided with a rearwardly and downwardly projecting hook-like member 43 adapted to engage over the flange or bezel 4 of the lamp body. The flange 42 will abut the glass 5 to retain the glass in place, and in the lower portions of the band 41, I provide an ear 44 centrally apertured as at 45 to receive a screw 46 which is threaded for engagement in the sleeve 32. This very simple expedient for securing the glass not only makes simple the original assembly of the device but also facilitates greatly the removal of the glass for cleansing or for the replacement of a lamp. Moreover, the arrangement is such that the possibility of accidental loss and breakage of the glass is remote, and so likewise is the possibility of the glass being rendered unremovable through corrosion.

It will be seen from the foregoing description of this invention how easily the several parts of this lamp can be manufactured and assembled in rigid and per-

manent form. It will be noted further that the lamp base and body, through their connection with the standard, are not only retained in their proper relative positions but also retain in proper form the standard itself, through the fact that the tongues 23 at either end of the blank from which the standard is formed are interlocked within a single recess in the disk portion 6 of the body. It will be observed further that the socket sleeve 35 performs a triple function in that it not only provides for the operative connection of plug 50 with lamp 60 but also re-enforces the standard and secures in position without further bolts, solder, or the like the screw-threaded sleeve 32 to which the ring 40 is fastened. In this last function, the standard itself co-operates by providing a recess in which is disposed the base flange 33 of sleeve 32.

I claim:

1. In a device of the character described, the combination with a lamp body having a marginal flange adapted to receive a glass front, of a ring provided with a hook engaged over said flange, said ring being operatively arranged to retain a glass against said flange, an ear projecting from said ring, a lamp standard connected with said body and providing a threaded socket, and a securing screw engaged in said socket and connected with said ear, whereby to removably co-operate with said hook to retain said ring and said glass in place.

2. As an article of manufacture, a casing for a vehicle lamp comprising a cylindrical wall having an integral flat disk portion adapted to be connected to a supporting member, said flat portion lying partially within and partially outside of the curve of said cylindrical wall so as to produce a minimum of distortion of the metal of the wall.

3. In a device of the character described, the combination of a lamp standard having a tubular wall with a portion pressed outwardly to provide a recess having a central aperture, a fitting extending through said aperture and flanged within said recess, and a member filling said standard and confining said flange within said recess.

4. In a device of the character described, the combination with a tubular standard having a laterally opening aperture and an adjacent recess, of an internally threaded sleeve extending through said aperture and provided with a flanged base fitted within said recess and adapted to co-operate with the walls thereof to secure said sleeve against rotation, and means fitted within said standard and extending transversely thereof to confine said flange within said recess.

5. In a device of the character described, the combination with a lamp body of gen-

erally cylindrical contour providing a substantially plane surface in its bottom and a lamp base providing a corresponding surface, both of said surfaces being apertured and having notches disposed at intervals about the margins of the apertures, of a tubular standard provided with tongues projecting through the notches of said apertures and having a recess formed in the inner surface of its wall and a laterally opening hole centrally of said recess, a fitting including a screw-threaded member projecting through said hole and provided with a flanged base complementary to said recess, and a bezel ring apertured in substantial registry with said fitting and provided remote from said aperture with means interlocking with said body.

6. In a device of the character described, the combination with a lamp body of generally cylindrical contour providing a substantially plane surface in its bottom and a lamp base providing a corresponding surface, both of said surfaces being apertured and having notches disposed at intervals about the margins of the apertures, of a tubular standard provided with tongues projecting through the notches of said apertures and having a recess formed in the inner surface of its wall and a laterally opening hole centrally of said recess, a fitting including a screw-threaded member projecting through said hole and provided with a flanged base complementary to said recess, a bezel ring apertured in substantial registry with said fitting and provided remote from said aperture with means interlocking with said body, and a sleeve fitted within said standard and confining the flange of said fitting within said recess.

7. In a device of the character described, the combination with a lamp body of generally cylindrical contour providing a substantially plane surface in its bottom and a lamp base providing a corresponding surface, both of said surfaces being apertured and having notches disposed at intervals about the margins of the apertures, of a tubular standard provided with tongues projecting through the notches of said apertures and having a recess formed in the inner surface of its wall and a laterally opening hole centrally of said recess, a fitting including a screw-threaded member projecting through said hole and provided with a flanged base complementary to said recess, a bezel ring apertured in substantial registry with said fitting and provided remote from said aperture with means interlocking with said body, and a sleeve fitted within said standard and confining the flange of said fitting within said recess, said sleeve providing a lamp socket within said body.

8. In a device of the character described, the combination with a lamp standard com-

prising a split ring having tongues projecting laterally from its ends, of a lamp base, and a lamp body provided with apertures registering with the opening through said 5 ring and having notches in the margins of said apertures to receive said tongues; and a re-enforcing sleeve disposed internally of said standard and maintaining said tongues expanded into said notches.

10 9. In a device of the character described, the combination with a lamp standard comprising a split ring having tongues projecting laterally from its ends, of a lamp

base, and a lamp body provided with apertures registering with the opening through 15 said ring and having notches in the margins of said apertures to receive said tongues; and a re-enforcing sleeve disposed internally of said standard and maintaining said 20 tongues expanded into said notches, said sleeve being provided with arcuate ribs intermediate its ends and adapted to abut said tongues and thereby to define the position of said sleeve.

ROBERT K. WINNING.
